MIXING DEVICE

Walter Van Guilder, Oak Park, Ill., assignor to
General Electric Company, a corporation of
New York

Application May 23, 1935, Serial No. 22,993

4 Claims. (Cl. 259—102)

This invention relates to mixing devices, more particularly to power operated food mixing devices, and it has for its object the provision of an improved beating tool in devices of this character.

In one of its aspects, this invention contemplates the provision of an improved mixing tool provided with suitable beating elements and arranged so that the tool automatically selects the correct beating or mixing speed for the elements responsive to the consistency of the material being mixed.

In accordance with this invention, the mixing tool, in one form thereof, is provided with a driving shaft which is arranged to be driven by the mixing machine that usually is provided with an electric motor for operating the shaft. One or more—preferably two—beating elements are mounted to rotate in a suitable supporting yoke, which in turn is arranged to rotate about the driving shaft as an axis. The driving shaft is positively connected, as by gearing, to the beating elements so that when the shaft is operated the beating elements will be rotated on their own axes in the yoke. Moreover, the yoke will be rotated about the driving shaft as an axis due to the resistance of the material being beaten to the rotation of the beating elements. The speeds of rotation of the beating elements and of the yoke depend upon the consistency of the material being worked.

For a more complete understanding of this invention, reference should be had to the accompanying drawing, in which Fig. 1 is an end elevation of a mixing device provided with a beating tool arranged in accordance with this invention; Fig. 2 is an enlarged vertical elevation, partly in section, of a beating tool arranged in accordance with this invention; Fig. 3 is a sectional view taken through the line 3—3 of Fig. 2 with certain parts of the tool removed so as to illustrate certain structural details; and Fig. 4 is a diagrammatic view illustrating the operation of the beating tool.

Referring to the drawing, this invention has been shown in one form as applied to a mixing tool 10 comprising a pair of beating elements 11. The beating elements 11 are rotatably mounted in a suitable supporting yoke 12. As shown, each beating element 11 comprises a pair of wire loops 13 and 14 arranged at right angles to each other, and rigidly secured to each other at their upper and lower ends. At their lower ends, the loops preferably are secured by spot welding, while the upper ends of the loops

are secured to a driving hub 15. The loops 13, as shown in Figs. 1 and 2, are considerably wider than the loops 14.

The hubs 15 are rotatably mounted upon stud shafts 16 that are rigidly secured to the yoke 12. For this purpose, the upper ends of the stud shafts are received in suitable bores 17 provided for them in the yoke, and are provided with rough knurled portions 18 arranged to coat with the metal walls of the yoke to prevent movement of the shafts 16 relative to the yoke.

Mounted upon each of the hubs 15 is a driving gear 19. It will be understood that the gears 19 are rigidly secured to the hubs so as to rotate with them. The lower ends of the hubs 15 pass through suitable apertures provided for them in the loops 13 and 14, as clearly shown in Fig. 2, and are provided on their lower ends beneath the loops with shoulders 20. Resting upon the shoulders 20 below the loops are washers 21 and mounted above the loops are second washers 22. Between these washers and the gears 19 are suitable spacer sleeves 23. The upper end of each hub is provided with a flange 24 which bears against the gear 19. In view of the foregoing arrangement, it will be observed that the hubs 15 are rigidly secured to the beater elements 11 and to the driving gears 19 for the beater elements. The lower ends of the driving hubs 15 and the shafts 16 are closed by means of suitable covers 25.

Preferably and as shown, the yoke will be so arranged that its walls define a chamber 26 in which the gears 19 are rotatably mounted. Also mounted within this housing is a main driving gear 27 which is rigidly secured to the driving shaft 28.

The yoke 12 is provided with bearings 29 to rotate upon the shaft 28. The bearings 29, as shown, are arranged in a bore 30, each bearing being provided with a flange 31 fitted over the ends of the bore, as shown in Fig. 2. The upper bearing 29, as viewed in Fig. 2, is held within the bore by means of a collar 32 rigidly secured to the shaft 28, while the lower bearing is secured in place by means of the driving gear 27. For this purpose, the end of the driving shaft 28 is provided with a threaded portion 33 which receives a nut 34. The nut 34, as shown, secures the gear 27 to the driving shaft. The nut also has a non-circular cross-section, such as a rectangular section, which is received in an aperture of corresponding shape in the gear 27, whereby a driving connection is effected between the driving shaft and the gear.

As shown, the beating elements are arranged to rotate on axes substantially parallel with each other and with the axis of the shaft 28, and substantially equidistant from the axis of shaft 28.

- 5 In the particular tool shown, the shaft 28 drives the gear 27 in a clockwise direction looking upwardly at the gear, as indicated by the arrow, in Fig. 4, while the gears 19 are driven in a counter-clockwise direction, as indicated by the arrows associated with them. When the beating elements are rotated in this direction, the tendency is for the yoke 12 to rotate in a clockwise direction, as indicated by the dotted circle in Fig. 4 and the arrow associated with it.
- 10 The lower ends of the beating elements are supported in spaced relation relative to each other by means of a wire supporting member 35. The wire supporting member is provided at its ends with up-turned portions 36, as shown in Fig. 2, received in suitable apertures provided for them in the lower ends of the loops 13 and 14.
- 15 The chamber 26 is closed by a cover 37 which, as shown, is provided with apertures for receiving the spacer sleeves 23. The cover is made in two parts 37a and 37b (Fig. 3), each of which is secured to the yoke 12 by means of a snap spring 38 secured to the housing and engaging ears 37c provided on the cover member.
- 20 The driving shaft 28 may be driven by any suitable power driven mixing device, such as that shown in Fig. 1. As shown, in this figure, there is provided a housing 39 in which a suitable operating motor (not shown) is mounted. This motor drives a flexible shaft 40 mounted in a suitable casing 41. The shaft 28 is arranged to be mechanically connected to the operating shaft 40 by any suitable mechanical connection 42, the details of which form no part of this invention, and which have not been shown in detail.
- 25 40 Associated with the power device 39 is a suitable receptacle 43 in which the beater tool 10 is arranged to operate.

In the operation of the device, it will be understood that the driving shaft 28 will be driven from the motor mounted in the base 39 through the flexible shaft 40. When the shaft 28 is operated, it will of course operate the driving gear 27, which in turn will operate the gears 19 secured to the beater elements 11, and the yoke 12 due to the reaction of the food being mixed on the beater elements 11.

In other words, the driving torque of the shaft 28 is divided into a force applied to rotate the yoke 12, about the shaft 28 as an axis, which of course swings the beater elements 11 as a whole about the shaft 28 as an axis, and a second force applied to rotate the beater elements about their own axes on the shafts 16. The speed of rotation of the beater elements 11 on their own axes, and that of the yoke 12 on the shaft 28 as an axis will depend upon the consistency of the material being beaten. Thus for example, if the beater is operating in a mixture having a very light consistency, the resistance against rotation of the entire tool including the yoke 12, together with the beater elements 11 mounted thereon, around the shaft 28 as an axis will be very slight, and consequently, the beater elements 11 will be swung around in the bowl 43 at practically the speed of the driving shaft 28, and will rotate at a very slow speed on their own axes. However, if the mixture is thickened, the resistance to rotation of the entire unit on the shaft 28 becomes greater, and as a result, the yoke slows down and the rotation of the beaters 11 on their own axes in-

creases. If the mixture be made still thicker, the yoke will slow down still more, while the speed of the beater elements will increase proportionately.

The operation of the beating tool depending upon the consistency of the material being beaten affords a safety device which prevents over-loading of the motor driving the shaft 28, because when the mixture becomes very heavy it merely means that the beating elements 11 will rotate at a higher speed on their own axes while the yoke 12 will slow down.

Furthermore, it will be observed that the beating tool automatically selects the most efficient speed for beating as well as requiring the minimum power.

While I have shown a particular embodiment of my invention, it will be understood, of course, that I do not wish to be limited thereto since many modifications may be made, and I, therefore, contemplate by the appended claims to cover any such modifications as fall within the true spirit and scope of my invention.

What I claim as new and desire to secure by Letters Patent of the United States is:

1. A mixing device comprising a driving shaft, means for driving said shaft, a beating element adapted to act upon materials to be mixed, a support for said beating element, a shaft on said support mounting said beating element for rotation on said support on an axis removed from the axis of said driving shaft, means mounting said support for free rotation about said shaft as an axis, and means mechanically connecting said beating element with said driving shaft so that said element will be positively driven on its shaft by rotation of said driving shaft and said supporting means is driven on said driving shaft as an axis due to the reaction of said materials on said beating element at speeds dependent upon the consistency of said material.

2. In a mixing device provided with an operating shaft, a beating tool adapted to act upon material to be mixed comprising a driving shaft adapted to be driven by said operating shaft, a support journaled on said driving shaft for free rotation thereon, beating elements mounted on said support for rotation on axes symmetrically arranged with reference to the axis of rotation of said driving shaft and of said support on said driving shaft and gearing between said beating elements and said driving shaft whereby said elements are positively driven on their axes in said support by the operation of said driving shaft and said support is rotated on said shaft to move said beating elements bodily around said shaft as an axis due to the reaction of said material on said elements.

3. In a mixing device provided with an operating shaft and means for driving said shaft, a mixing tool comprising a driving shaft adapted to be driven by said operating shaft, a frame journaled on said driving shaft for free rotation relative to said shaft and about said shaft as an axis, a pair of beater elements symmetrically arranged on opposite sides of said shaft and journaled in said frame for rotation on axes parallel with each other and with the axis of said driving shaft, gears secured to said beater elements and a gear secured to said driving shaft meshing with said gears secured to said beater elements.

4. In a mixing device provided with a driving motor, a beating tool comprising a shaft adapted to be driven by said motor, a frame provided with

walls defining a housing, means journaling said frame for free rotary motion upon said shaft, a pair of beater elements journaled in said frame on opposite sides of the axis of rotation of said shaft, gears within said housing secured to said beater elements, and a gear within said housing secured to said shaft meshing with said gear secured to said beater element, whereby motion

is positively imparted to said elements to rotate on their own axes in said frame and said frame together with said elements is rotated as a whole about said shaft as an axis due to the reaction of the materials worked upon to the action of said beater elements. 5
